(57) **CLAIM**

The ornamental design for a speaker stand, as shown and described.

DESCRIPTION

FIG. 1 is a front left perspective view of a speaker stand showing our new design;

FIG. 2 is a front top perspective view thereof;

FIG. 3 is a front right perspective view thereof;

FIG. 4 is a back left perspective view thereof;

FIG. 5 is a front elevation view thereof;

FIG. 6 is a top plan view thereof;

FIG. 7 is a right side elevational view thereof, the left side elevational view being a mirror image;

FIG. 8 is a back elevation view thereof;

FIG. 9 is a bottom plan view thereof;

FIG. 10 is a top, front, right perspective view of the speaker stand of FIG. 1 showing an alternative possible orientation of the speaker stand with respect to a speaker.

FIG. 11 is a side right perspective view of the speaker stand of FIG. 10.

FIG. 12 is a rear perspective view of the speaker stand of FIG. 10; and,

FIG. 13 is a front, right perspective view of the speaker stand of FIG. 10.

The broken lines showing the speaker and feet in FIGS. 1-13, control knobs and stand mounting portion in FIGS. 1, 4, and 7-9 are for illustrative purpose only and form no part of the claimed design.
